BRAKE DEVICE FOR SEWING MACHINES

William L. Barron, Laurence Harbor, N. J., assignor to The Singer Manufacturing Company, Elizabeth, N. J., a corporation of New Jersey

Application September 19, 1936, Serial No. 101,564

7 Claims. (Cl. 112—218)

This invention relates to sewing machines, and it has, as its primary object, to prevent accidental reciprocation of the needle during the winding of bobbins.

As commonly constructed, each sewing machine includes a main shaft, a hand- or balance-wheel normally secured thereto at one end, means actuated by the main shaft to reciprocate the needle-bar, and means, either manual or power, for rotating the balance-wheel and thereby the main shaft. It is also common practice to fit each machine with a bobbin-winder adapted to be operated either by the rotation of the balance wheel or by the drive therefor.

Inasmuch as the bobbin-winding operation is separate and distinct from the sewing operation, it is desirable that, during the bobbin-winding operation, the stitching mechanism be rendered ineffective. Therefore it is customary to provide friction clutch means between the balance-wheel and the main shaft so that the balance-wheel may be uncoupled from the shaft and be rotated idly thereon during the bobbin-winding operation.

In recent years improvements in sewing machines have made them so light running that the slightest sticking of the balance-wheel clutch, when released, or even the friction of the balance-wheel on the main shaft is sometimes sufficient to cause the needle-bar to be reciprocated.

Another object of this invention therefore is to provide means for preventing accidental reciprocation of the needle-bar during the bobbin-winding operation and so to construct such means that it may readily be applied, as an attachment, to sewing machines now in use.

Still another object of the invention is so to construct the device that it will be rendered effective to maintain the needle-bar stationary by the normal operations incident to a bobbin-winding operation, and therefore will not impose any additional duty on the operator.

With the above and other objects in view, as will hereinafter appear, the invention comprises the devices, combinations and arrangements of parts hereinafter described in connection with the accompanying drawings which illustrate a preferred embodiment of the invention, and in which:—

Fig. 1 is a side elevation, partly in section, of a sewing machine embodying the present invention.

Fig. 2 is a left end view of a portion of Fig. 1

showing in full lines, the parts in sewing position and the needle-bar restraining means in its ineffective position.

Fig. 3 is a fragmentary left end view of the machine illustrated in Fig. 1, showing the needle-bar restraining means in its effective position.

Fig. 4 is a detail perspective view of the needle-bar restraining device showing it secured to the presser-bar of a sewing machine.

Fig. 5 is a horizontal sectional view taken on the line 5—5 of Fig. 3.

Fig. 6 is a detail perspective view of one of the elements of the needle-bar restraining means.

Referring more specifically to the drawings, the invention is disclosed as embodied in a sewing machine comprising a bed plate 1, standard 2, overhanging arm 3 and head 4. Within the arm 3 is journaled, in bearings 5 and 6, a main or needle-bar driving shaft 7 to the rear end of which is adapted to be secured a hand- or balance-wheel 8. The balance-wheel is preferably formed with a hub 8^a rotatably journaled on a sleeve 9 secured to the shaft 7, by a pin 10. The balance-wheel is adapted to be rotated by any suitable means, such for example as by an electric motor M, the shaft 11 of which carries a gear 12 which meshes with and drives a supplemental gear 13 secured to the hub of the balance wheel. The sleeve 9 is formed with a shoulder 14 against which a corresponding shoulder 15, within the hub 8^a, is clamped by a manually operated clamp screw 16 having a knurled head 17. The clamp screw is threaded into the outer end of the sleeve 9 and bears against a washer 18 which in turn bears against the balance wheel 8 to force the shoulders 14 and 15 into driving contact. The shoulders 14 and 15 and the washer 18 and hub 8^a form a friction clutch which, when in driving contact, causes the main shaft 7 to be rotated with the balance-wheel. A bobbin-winder W, shown partially in Fig. 2 is secured to a portion of the motor casing and is adapted to be operated by contact with an annular flange 19 formed on the balance wheel. Preparatory to a bobbin-winding operation the balance wheel clutch is released so that the bobbin may be wound without rotating the main shaft and without actuating the parts connected therewith.

The above described drive, clutch and bobbin-winding means are of conventional form and are disclosed in detail in U. S. patent to W. J. Peets, No. 1,934,373, Nov. 7, 1933, to which reference

may be had for a more complete understanding thereof.

At its forward end, the shaft 7 has secured thereto a take-up actuating cam 20. This cam 5 carries a crank-pin 21 which is connected by a link 22 to a needle-bar 23 mounted in bearings 24 and 25 provided by the head 4. Thus, rotation of the main shaft effects reciprocation of the needle-bar and a needle 26 carried thereby.

10 A presser-bar 27, carrying a presser-foot 28, also is mounted in the head 4 and is urged downwardly by a spring 29 in the usual manner. A presser-lifting lever 30 is pivotally mounted on a stud 31 secured in the head 4 and has a cam surface 32 which engages beneath a finger 33 carried by a collar 34 secured to the presser-bar. The collar 34 also has an arm 35 which projects at right angles to the finger 33 and which is slidably fitted between the walls of a groove 36 15 milled in the head 4, (Figs. 1 and 5) thereby to prevent rotation of the presser-bar in the head.

As hereinbefore indicated, this invention provides means to place an abnormal drag on a moving part of the machine and thereby prevent reciprocation of the needle-bar during the bobbin-winding operation if the balance-wheel clutch should stick or should any other minor force tend to turn the main shaft when the clutch is released. This has been accomplished by providing a normally ineffective brake mechanism adapted to be rendered effective by the lifting of the presser-foot, which latter is done preparatory to a bobbin-winding operation.

This brake device may be in the nature of an 35 attachment adapted to be applied to sewing machines now in use and comprises a spring arm 37 secured, as by a rivet 38, to one portion of a split collar 39 adapted to be clamped to the presser-bar 27, as by a clamp-screw 40. The collar 39 is preferably made of two parts 39^a and 39^b so that it may readily be applied to machines now in use, without disassembling the machine. The part 39^a carries the spring arm 37 and is formed with an upwardly extending portion 41 40 having an offset finger 42 adapted to slidably fit within the above mentioned milled groove 36 formed in the head 4, thereby to prevent the collar 38 and the parts carried thereby, from turning on the presser-bar.

50 The spring arm 37 is formed with a curved free end 37^a which, as shown in full lines in Fig. 2, is normally maintained out of the path of travel of the link 22 during the operation of the sewing machine. However, when the presser-foot is lifted, for the purpose of winding bobbins, the cam portion 32 of the lifter 30 engages an intermediate portion 37^b of the spring arm 37 and forces the end 37^a thereof into the path of the lower end of the link 22, as shown in dotted lines in Fig. 2 and in full lines, Figs. 3 and 5. With the arm in this position, should the link tend to descend accidentally due to sticking of the balance-wheel clutch or from other causes, it will engage the free end 37^a of the arm 33 55 which will restrain the downward movement of the link and the needle-bar connected thereto sufficiently to overcome the impositive movement thereof. Should the presser-foot be raised and the needle-bar be driven positively no damage 60 will result as the brake arm 37 will merely be deflected out of the path of the link 22 at each reciprocation thereof.

From the foregoing it will be perceived that I 75 have provided a simple means in the nature of an attachment, which may be applied to machines

now in use, for preventing accidental reciprocation of the needle-bar and needle during a bobbin-winding operation. Also that no additional duty is imposed upon the operator to render the device effective, the operator merely performing the usual steps incident to the winding of a bobbin.

Having thus set forth the nature of the invention what I claim herein is:—

1. A sewing machine combining a reciprocating needle-bar; a presser-foot; driving means for said needle-bar; lifting means for said presser-foot; disconnecting means between said needle-bar and its driving means; means actuated by said driving means when it is disconnected from said needle-bar to wind bobbins; and means, rendered effective by the actuation of said presser-foot lifting means, to prevent accidental movement of said needle-bar after said disconnecting means has been actuated to disconnect 20 said needle-bar from its driving means.

2. A sewing machine combining a reciprocating needle-bar; a presser-bar; driving means for said needle-bar; lifting means for said presser-bar; disconnecting means between said needle-bar and its driving means; means actuated by said driving means when it is disconnected from said needle-bar to wind bobbins; and means secured to said presser-bar and rendered effective by said presser-bar lifting means to prevent accidental movement of said needle-bar after said disconnecting means has been actuated to disconnect 25 said needle-bar from its driving means.

3. A sewing machine combining a head; a reciprocating needle-bar therein; driving means for 35 said needle-bar, including a rotary shaft and a crank-and-link mechanism between said shaft and said needle-bar; means to disconnect said needle-bar from its driving means; means actuated by said driving means when it is disconnected from said needle-bar to wind bobbins; and a normally ineffective impositive brake device located within said head and adapted to act upon a portion of said needle-bar driving means when said bobbin-winding means is in operation 40 to prevent accidental reciprocation of said needle-bar.

4. A sewing machine combining a reciprocating needle-bar; driving means therefor comprising a rotary crank and a link connecting the 50 crank with said needle-bar; means to disconnect said needle-bar from its driving means; means actuated by said driving means when it is disconnected from said needle-bar to wind bobbins; and a spring brake device acting on said link 55 when said bobbin-winding means is in operation, to prevent accidental reciprocation of said needle-bar.

5. An attachment for sewing machines having a reciprocating needle, driving means therefor, a 60 presser-bar, means to disconnect said needle from its driving means, and means actuated by said driving means when it is disconnected from said needle to wind bobbins; comprising a spring brake device adapted to be secured to said presser- 65 bar and to engage said needle driving means to prevent accidental reciprocation of said needle when it is disconnected from its driving means.

6. An attachment for sewing machines having a reciprocating needle-bar, a presser-bar, driving 70 means, including a power driver, for said needle-bar, lifting means for said presser-bar, disconnecting means between said needle-bar and its driving means, and means actuated by said driving means when it is disconnected from said 75

needle-bar to wind bobbins; comprising a collar adapted to be secured to said presser-bar; and a spring arm carried by said collar, said arm having a portion adapted to lie within the range 5 of movement of said presser-bar lifting means whereby said arm will be shifted by said lifting means into the path of movement of a portion of said needle-bar driving means, thereby to prevent accidental reciprocation of said needle-bar 10 after said disconnecting means has been actuated to disconnect the needle-bar from its power driver.

7. An attachment for sewing machines having a head, a presser-bar, a reciprocatory needle,

means including a prime mover for driving said needle, and means to disconnect said needle from said prime mover; said attachment comprising a split collar adapted to be secured to said presser-bar; a finger projecting laterally from said collar and engaging a fixed portion of said head to prevent rotation of said collar on said presser-bar; and a spring arm secured to said collar and having a portion adapted to engage said needle driving means to prevent accidental reciprocation of said needle when it is disconnected from said prime mover. 5 10
